UNITED STATES PATENT OFFICE.

ROBERT A. RUTHERFORD, OF PHILADELPHIA, PENNSYLVANIA, ASSIGNOR TO
THE PEDRICK & AYER COMPANY, OF SAME PLACE.

VALVE DEVICE FOR PNEUMATIC HOISTS.

SPECIFICATION forming part of Letters Patent No. 675,528, dated June 4, 1901.

Application filed October 11, 1900. Serial No. 32,685. (No model.)

To all whom it may concern:

Be it known that I, ROBERT A. RUTHERFORD, a citizen of the United States, residing at No. 768 Martin street, Philadelphia, in the county of Philadelphia and State of Pennsylvania, have invented certain new and useful Improvements in Valve Devices for Pneumatic Hoists, of which the following is a specification, reference being had therein to the accompanying drawings.

This invention relates to an improved valve device applied to a pneumatic hoist of the type referred to in Letters Patent of the United States No. 646,458, dated April 3, 1900, where-
15 in in operation pressure is admitted to both sides of the hoisting-piston to establish an equilibrium of pressure and exhausted alternately from the upper side of the piston to the atmosphere to elevate the piston and lift the
20 load and from the lower side of the piston to its upper side to depress the piston and lower the load. In the patent referred to a relief-valve independent of the operating-valve is adapted to automatically open the communica-
25 tion between the upper side of the piston and the atmosphere to reduce the pressure above the piston when the piston incidentally settles or moves downward and close when said pressure is reduced to a degree to check
30 said downward movement and permit the piston to return to its normal suspended position.

In the present invention a valve is adapted to communicate with either side of the piston and automatically govern either an upward or downward similar movement thereof.

The present invention consists in a separate and independent valve device communicating with the supply-pipes leading to the
40 opposite sides of the piston and with the atmosphere operated by devices controlled by a movement of the piston in either an upward or downward direction and adapted to automatically change the pressure upon the
45 opposite sides of the piston, so as to maintain and hold it in a given position.

In the accompanying drawings, Figure 1 is a side elevation, partly in section, showing all the essential parts of the hoist; Fig. 2, a

plan view of the auxiliary valve, and Fig. 3 a central plan view of the casing of the main valve device.

A represents the cylinder, within which a hoisting-piston is affixed to the piston-rod b in the usual manner, the load being connected 55 at the lower end of the piston-rod.

The main valve device that controls the fluid-pressure supply that operates the hoist is contained in the casing o and communicates with the cylinder A through the orifice R, which is open to the pipe s, leading from the source of the fluid-supply. This main valve device forms no part of the present invention, it being referred to and claimed in another application for a patent filed by me 60 August 9, 1900, Serial No. 26,334, the pipes s and v, valves D and P within the respective chambers II and K, the springs h and m, valve-rods r and n, the communicating passage N, the passage D² to the atmosphere, 65 and the operating-lever L², vibrating upon the pivot z, being counterparts of the device referred to in said application. In said application the mechanism for automatically maintaining the suspended load in its 70 elevated position connects with the operating-lever L² and acts only to relieve the pressure from the upper side of the piston when the piston settles downwardly with the suspended load, the effect being to arrest and 75 restore the piston and load to the normal suspended position. In the present instance a separate and independent valve device is employed, adapted to automatically distribute the pressure upon either side of the pis- 80 ton to check either its upward or downward movement and maintain the load in its de- 85 sired suspended position. This separate and independent valve is shown at A² and is constructed with passages J' J², that register 90 with the ports I' I², leading to the pipes s and v, which communicate with the respective sides of the piston in the main cylinder A and with the port c, that opens to the atmosphere. This valve A² is oscillated by means of the 95 lever B, connecting-rod C², and vibrating lever E², the latter being pivoted to a rigid post F depending from the main cylinder, and

coupled at *e*, with a friction-clutch *E* placed upon the piston-rod *b*. The clutch *E* is similar to that shown in my former application and its degree of friction regulated to operate the valve *A*² and also allow the piston-rod to move therethrough after the limited movement of the valve *A*² is effected.

The main valve device is operated through the rocking lever *L*² directly by hand or by chains or rods connected at each extremity, the valve- rods *r* and *n* being alternately forced upwardly, when the lever *L*² is accordingly rocked to bring the end of the respective rods in contact therewith.

15 In operation to raise the load the valve *P* is first lifted, which opens communication from the upper side of the piston to the atmosphere through the pipe *v* and escape-passage *D*², the pressure-supply through the pipe *s* being in open communication with the lower side of the piston through the opening *R*. When the load has reached the desired elevation, the movement of the lever *L*² is reversed, which opens the valve *D*, and simultaneously the valve *P* is seated by the spring *m*, which closes the communication with the atmosphere, and the pressure-supply is admitted to the upper side of the piston from the chamber *H* through the passage *N* and pipe *v*, whereby an equilibrium of pressure is established on both sides of the piston. The lever *L*² is now brought to its horizontal position, which permits the valves *D* and *P* to seat, and the piston is thereby held in its elevated position by the confined pressure on its opposite sides. When it is desired to lower the piston and its load, the lever *L*² is rocked to open the valve *D*, which opens communication between the pressure-supply and both sides of the piston, which is thereby forced downwardly by the supply-pressure acting upon the greater superficial area of its upper side in amount equal to the area occupied by the piston-rod upon 45 its lower side, the pressure beneath the piston being transferred in the movement to its upper side. During the suspension of the load the natural tendency of the piston is to lower or settle downwardly, due principally to 50 leakage, and this condition has been met and remedied by devices referred to in the Letters Patent and in the specification heretofore mentioned.

In the present invention the device for correcting this incidental downward movement

is also adapted to apply to a corresponding upward movement of the piston.

In the position shown in Fig. 1 of the drawings the valve *A*² is open to the upper side of the piston through the port *I*² and pipe *v* and closed to the supply-pipe *s* and lower side of the piston and the port *c* to the atmosphere. A downward movement of the piston will, through the connecting mechanism with the piston-rod, turn the valve so that the port *J*² will register with the port *I*², leading to the pipe *v*, and the port *c*, leading to the atmosphere. This will relieve the pressure from above the piston sufficient to arrest its movement and cause it to return to its normal suspended position, the return movement also returning the valve *A*² to its former position, and to close the escape-port *c*. An upward movement of the piston will by the same instrumentalities operate the valve to open communication between the supply-pipe *s* and pipe *v*, leading to the upper side of the piston, respectively, through the port *I*', valve-port *J*², and port *I*², thus transferring the supply-pressure to the upper side of the piston, and thereby checking its upward movement and returning it to its normal suspended position, the balancing pressure acting on its preponderating area, the movement also causing the valve *A*² to return to its starting-point, thus closing the communication with the supply-pipe *s* and checking the further downward movement.

Having thus fully described my invention, what I claim, and desire to secure by Letters Patent, is—

In a pneumatic hoist comprising a cylinder, piston and piston-rod and valve device whereby in operation the motive fluid may be admitted to establish an equilibrium of pressure upon both sides of the piston, an auxiliary valve device adapted to communicate with the supply-pipes leading to the respective sides of the piston and to the atmosphere, and means for automatically operating said valve device, so that the pressure is adjusted to check a movement of the piston from its suspended position in either an upward or downward direction, as set forth.

In testimony whereof I affix my signature in presence of two witnesses.

ROBERT A. RUTHERFORD.
